(57) CLAIM

The ornamental design for a knife, as shown and described.

DESCRIPTION

FIG. 1 is a perspective view of a knife, with a blade portion shown in dashed lines herein and throughout for illustrative purposes only and forming no part of the claims design; FIG. 2 is a bottom plan view thereof;

FIG. 3 is a top plan view thereof;

FIG. 4 is a front elevational view thereof;

FIG. 5 is a rear elevational view thereof;

FIG. 6 is a side elevational view thereof, the opposite side being a mirror image hereof; FIG. 7 is a perspective view of the knife in another embodiment of the design;

FIG. 8 is a bottom plan view thereof;

FIG. 9 is a top plan view thereof;

FIG. 10 is a front elevational view thereof;

FIG. 11 is a rear elevational view thereof; and,

FIG. 12 is a side elevational view thereof, the opposite side being a mirror image hereof.
